UNITED STATES PATENT OFFICE.

GIUSEPPE MAZZOLINI, OF ROME, ITALY.

MEANS FOR REMOVING COAL AND OTHER FOREIGN BODIES FROM COAL-BUNKER
DOORS OR OTHER WATER-TIGHT CLOSURES ON SHIPS.

1,084,701.

Specification of Letters Patent.

Patented Jan. 20, 1914.

Application filed May 2, 1912. Serial No. 694,643.

To all whom it may concern:

Be it known that I, GIUSEPPE MAZZOLINI, a subject of the King of Italy, residing at Rome, Italy, gentleman, (whose post-office address is 19 Via delle Quattro Fontane, Rome, Italy,) have invented certain new and useful Improvements in Means for Removing Coal and other Foreign Bodies from Coal-Bunker Doors or other Water-Tight Closures on Ships, of which the following is a specification.

My present invention is an improvement of my prior device protected by U. S. Patent No. 1,022,688, and has for its object to provide an improved means for removing coal and other foreign bodies from coal bunker doors or other water tight closures on ships, such as illustrated by way of example in the annexed drawings where—

20 Figure 1 is a front view of my improved protective device applied for use with a watertight door, Fig. 2 is a sectional view on line A—B of Fig. 1, while Fig. 3 is a side view of another arrangement of curved 25 levers.

According to my said invention, in order to efficiently protect from interfering foreign bodies, such as coal &c., those parts of bulkheads or other watertight doors where 30 the watertight closure is effected, the known protective plates (such as in my said prior U. S. patent) are assisted in their rotary movement by levers placed laterally to the frame which on descending cause other 35 levers placed in the bottom part of the frame to be raised, thus causing the said known protective plates to assist with their tilting the instantaneous closing movement of the door.

40 —1— and —2— in the present example are levers mounted parallel to the uprights or side-posts, and provided at their top ends with inward projecting teeth —3—, the door being provided with corresponding teeth 5 capable of striking in the descent the teeth —3—. The said levers —1— and —2— are guided by yokes —6— and pivoted to arms —7— of levers —8— pivoted in turn at —9—. Arms 10 and 11 of levers —8— are 50 curved in opposite direction from each other so as to be able to assist each other with their backs. Yokes —6— guiding the levers —1— and —2— are provided with longitudinal slots having inclined faces on which 55 glide the inclined faces —12— and —13—,

Fig. 2, fixed on the said levers —1— and —2—.

The plates —f— and —c— have swellings —f'— and —c'—, and so has plate —d— which in its center, at the lower part, 60 has an inclined face —d'— on which acts the lever arm —10—.

One of arms —7— of lever —8— may have an extension —14— provided with a slot —15— in which slides a stud fixed to 65 an arm —16— of a lever rotatably mounted at —17—. The other arm is pivotally connected to the end of the rod of a valve —18— controlling a water and air jet directed under high pressure through tubes 70 —19— and —20— on the sill so as to forcibly carry off any residual foreign bodies or detritus capable of interfering with the true watertight closure of the door. Simultaneously a set of teeth provided at the bottom 75 of the door strongly act on the residual coal pieces on the sill so crushing them that they may be readily swept off by the said air and water jet.

The operation of my above described improved protective device is as follows: When watertight doors are to be closed, the frame or door &c. —4—, as shown, on being lowered (by hand or distant operation) strikes with its projection —5— the teeth 80 —3— and continues to push, transmitting this movement to levers —1— and —2— so as to lower them. By this movement the levers —8— by rotating on their pivots —9— raise arms —10— and —11— which 85 in turn raise the plate or sill —d— and in the meantime pieces —21— —21'— are introduced so as to strike plates —c— —f— at the points bent to an inclined plane —z— —r— causing them to rotate inward and 90 push the coal or foreign bodies to the interior, the plates being moved to position —m—, and the door having continued to descend finds itself on the tight seat where it is compressed.

100 The above described device is sufficient to protect the abutting or tight closing edges of watertight doors against interfering foreign bodies so as to allow of their perfectly tight closure, the tight seat being perfectly cleared of foreign bodies. If, however, thorough cleaning is desired, the above mentioned mixed air and water jet will be put in operation. This rotary movement of the plates is also assisted in starting by the 105 110

projections —5— which after having struck the teeth —3— slide against the top bents of plates —f— —c— at the points —z— —r— and also lever arm —10— which 5 thus engages the inclined faces —d'—. Simultaneously with the descent of the door air and water jets may be started by the descent of levers —1— or —2—. Thus all 10 detritus and foreign bodies having been swept off, a perfect watertight closure is effected.

It is understood that the above described example is only given for illustrative purposes, the lever arms —10— and —11— being, for instance, capable of any relative position to each other, and of acting independently from each other, and also of taking the position at both parts —1—, and so are the two inclined faces —d—, the whole without departing from the scope of my said invention.

Having now fully described my said invention and the manner in which the same is 25 to be performed, I declare that what I claim as my invention is:

1. In a device of the class described, in combination, a door frame, a protective sill plate operatively associated therewith, said plate being rotatably mounted, whereby it 30 may be moved into and out of operative position, a door, and levers operatively associated with said plate for moving it into its inoperative position, said levers being actuated by the door as it moves to its closed position.

2. In a device of the class described, in combination, a door frame, a protective sill plate operatively associated therewith, said plate being rotatably mounted, whereby it 35

may be moved into and out of operative position, a door, levers positioned adjacent the side posts of the frame and provided with inwardly extending projections adapted to be actuated by the door as it moves to its closed position, and horizontal levers positioned below said frame, said horizontal levers being connected to said first-mentioned levers and being operatively associated with said sill plate to move the same into inoperative position upon actuation of said projections by said door.

3. In a device of the class described, in combination, a door frame, a door, a protective plate for the sill of said frame, protective plates for the sides of said frame, all 55 of said plates being rotatably supported, and means controlled by the closing movement of the door for moving said plates into their inoperative position, said side plates being provided with means engaging said 60 sill plate to assist in the movement of the latter.

4. In a device of the class described, in combination, a door frame, a door, a pipe 65 operatively associated with said door frame for directing fluid under pressure to sweep foreign matter from the sill of the frame, and means actuated by the closing movement of said door for controlling the flow of liquid through said pipe.

In testimony whereof I have signed my name to this specification in the presence of two subscribing witnesses.

GIUSEPPE MAZZOLINI.
